UNITED STATES PATENT OFFICE.

ROSS H. WAKEMAN, OF BRADENTOWN, FLORIDA.

GRAVE COVERING.

Application filed September 3, 1925. Serial No. 54,351.

This invention relates to covers especially adapted for use in connection with casket lowering devices.

Briefly stated, an important object of the invention is to provide a grave cover which is moved to an operative position over the grave and the casket solely by the weight of the casket and which effectively conceals the casket to lessen the unpleasantness of a burial.

A further and equally important object is to provide a grave cover which may be employed in connection with a conventional casket lowering device and which not in any way interferes with the freedom of movement of the pallbearers in placing the casket on the straps of the lowering device.

Also an aim of the invention is to provide a grave cover which is of highly simplified construction, and comparatively cheap to manufacture.

Other objects and advantages will be apparent during the course of the following description.

In the accompanying drawings forming a part of this application and in which like numerals are employed to designate like parts throughout the same:

Figure 1 is a plan view of the improved grave covering attachment ready for use;

Fig. 2 is an end elevation of the same in open position;

Fig. 3 is a vertical transverse sectional view through the improved grave covering attachment in open position;

Fig. 4 is a vertical transverse sectional view taken on line 4-4 of Fig. 1.

In the drawing, wherein for the purpose of illustration is shown a preferred embodiment of the invention, the numeral 5 designates a casket lowering apparatus of conventional design and which is provided with parallel longitudinal rotatable bars 6, about which the casket lowering straps 7 are trained. When the releasing device 8 is actuated the casket mounted on the two straps 7 is gradually lowered under the influence of its own weight and the weight of the contents thereof. It is a distressing sight to the mourners and others to observe the casket gradually descending into the grave and to avoid this it is proposed to provide a means whereby a covering is extended over the grave to conceal the lowering operation.

The improved covering mechanism comprises a frame 10 of the same outline as the

lowering apparatus as suggested in Figs. 1 and 2 and by reference to these figures it will be seen that the frame supports the lowering apparatus a slight distance above the grave. The ends of the frame or base member are provided with pairs of recesses 11 as shown in Fig. 3 and supporting ribs 12 are pivoted to the walls of the recesses 11 as shown at 14. The ribs 12 which may be of any suitable material have their upper ends connected to flexible strips or webbing 15 and the innermost ribs 12 have connection with one of the strips 16 of a flexible cover or screen 17. A second webbing or flexible strip 18 is arranged outwardly of the strip 15 and has connection with the longitudinal strips 16, all of which is shown in Fig. 3. The longitudinal strips 16 when swung to operative position support the screen or cover 17 to give the grave the form of a mound.

When the grave cover is in open position the ribs 12 will be partly positioned in the recesses 11 and will be approximately flush with the top of the frame whereby the frame acts as a protecting means for the ribs. In this connection it is also pointed out that when the grave cover is in open position the longitudinal supports 16 will be approximately flush with the top of the frame whereby the pallbearers and others may walk upon the supporting strips and the frame without damage thereto. In fact the covering 17 which is preferably in the nature of a raffia rug extends over and protects the strips 16 against damage.

It will be seen that the flexible covering 17 at each side of the improved grave cover moves away from the supporting ribs 12 when the grave cover is in an open position so as to permit the ribs to move to the fullest extent possible into the recesses 11.

The ends of the innermost strips 16 have detachable connection through the medium of hooks 20 with cover drawing strips or webbing 24 and the webbing 24 is trained about the rotatable bars 6 in directions opposite the direction of winding of the casket supporting straps 7. This arrangement results in the winding of the cover drawing members 24 on the bars as the casket is being lowered.

It will, therefore, be seen that as the casket is lowered into the grave under its own weight the cover will be gradually brought into position to conceal the casket and form

a temporary mound over the same. When the casket reaches a position approximately flush with the ground, the cover will be entirely closed and the undertaker may by operating the lever 8 stop further descent of the casket. However, this halt in the descent of the casket is only temporary and is continued after the mourners have left the scene. It will be readily appreciated that the use of this invention in connection with a casket lowering apparatus will avoid much of the unpleasantness ordinarily resulting from the more or less slow and plainly visible descent of the casket into the open grave.

When it is desired to complete the introduction of the casket into the grave, the hooks 20 are released and the cover will drop to open position by its own weight. This makes it possible for the undertaker to supervise and observe the completion of the burial.

The employment of the improved grave covering attachment will not in any way interfere with the casket lowering mechanism and may be employed in conjunction with the casket lowering mechanism to avoid unpleasantness and thereby greatly expedite the work of the undertaker.

Having thus described the invention, what is claimed is:—

1. The combination with a casket lowering device having rotatable strap supporting bars, of straps trained about said bars, and collapsible grave covers having detachable connection with said straps and adapted to be opened by said straps.

2. The combination with a casket lowering device having rotatable strap supporting bars, of straps trained about said bars, collapsible grave covers having detachable connection with said straps and adapted to be opened by the same, and a frame supporting said casket lowering device and having means to partially receive and protect said collapsible grave covers.

3. The combination with a casket lowering device having rotatable strap supporting bars, of straps trained about said bars, grave covers having detachable connection with said straps, and a frame supporting said casket lowering device and having means to partially receive and protect said grave covers, said grave covers being collapsible and being positioned approximately flush with the upper side of said frame when open, whereby the frame protects the covers from injury by the pallbearers.

4. An apparatus of the character specified

comprising a frame having recesses, radial members pivotally associated with said frame and adapted to be received in said recesses and protected by the walls of the same, flexible connecting strips secured to said radial members, flexible covers extended over said connecting strips, and casket operating means for moving said connecting strips and the flexible covers to open position over a casket whereby said covers will conceal the casket.

5. The combination with a casket lowering apparatus having rotatable bars, of flexible members trained about said bars and having hooks, collapsible frames arranged at opposite sides of said bars and engaged by said hooks, and a collapsible flexible cover connected to said collapsible members and adapted to be opened to extend over the casket lowering apparatus to conceal the grave and the casket.

6. The combination with a casket lowering apparatus having rotatable bars, of flexible members trained about said bars and having hooks, collapsible frames arranged at opposite sides of said bars and engaged by said hooks, a collapsible flexible cover connected to said collapsible members and adapted to be opened to extend over the casket lowering apparatus to conceal the grave and the casket, and a frame movably supporting said collapsible members and having recesses to partly receive the same.

7. A grave cover comprising a frame having recesses, ribs pivotally associated with said frame, connecting strips secured to said ribs, flexible covers extending over said connecting strips and adapted to be positioned at opposite sides of a grave, and casket operating means detachably connected to said strips to draw the same inwardly over a casket whereby the covers are positioned over the casket to conceal the lowering operation, said ribs being adapted to be received in said recesses.

8. The combination with a frame, of a casket lowering apparatus mounted on the frame and having rotatable bars, straps trained about said bars, ribs pivotally associated with said frame and positioned adjacent opposite ends of the same, supporting strips connected to said ribs, and separate covers extended over said strips and adapted to be drawn over a casket to conceal the lowering of the casket, said straps having detachable connection with certain of said strips.

In testimony whereof I affix my signature,
ROSS H. WAKEMAN.
